UNITED STATES PATENT OFFICE

119,291

DESIGN FOR A SHOE SOLE

Chikazo Watanabe, Los Angeles, Calif.

Application December 9, 1939, Serial No. 88,780

Term of patent 14 years

To all whom it may concern:

Be it known that I, Chikazo Watanabe, a subject of the Emperor of Japan, residing at 235 Jackson Street, in the city of Los Angeles, in the county of Los Angeles and State of California, have invented a new, original, and ornamental Design for Shoe Soles, of which the following is a specification, reference being had to the accompanying drawing, forming part thereof.

I claim:

The ornamental design for a shoe sole, as shown.

CHIKAZO WATANABE.
